UNITED STATES PATENT OFFICE.

HARRY W. WEYMANN, OF PHILADELPHIA, PENNSYLVANIA, ASSIGNOR TO H. A. WEYMANN & SON, INC., OF PHILADELPHIA, PENNSYLVANIA, A CORPORATION OF PENNSYLVANIA.

TUNING PEG FOR MUSICAL INSTRUMENTS.

Application filed April 14, 1923. Serial No. 632,002.

To all whom it may concern:

Be it known that I, HARRY W. WEYMANN, a citizen of the United States, residing at Philadelphia, in the county of Philadelphia and State of Pennsylvania, have invented 5 new and useful Improvements in a Tuning Peg for Musical Instruments, of which the following is a specification.

My invention relates to new and useful 10 improvements in a tuning peg for musical instruments, and has for its primary object to construct a device of this character which is particularly adapted for use on stringed musical instruments of the banjo type 15 wherein the key or finger piece may be rotated at one speed and the tuning peg proper rotated at a slower speed through the medium of a suitable mechanism actuated by the key.

Another object of the invention is to provide for varying the speed of rotation between a key or finger piece and a tuning peg so constructed that said key and tuning peg are in direct endwise alignment so that 25 the ordinary well known operation and appearance of device of this character will remain unchanged.

A further object of the invention is to provide a tuning peg, an operating peg or finger 30 piece in endwise alignment therewith and a train of gears for transmitting motion from the key to the tuning peg in such manner that the rotation of the tuning peg will be at a less speed than the rotation of the key.

A still further object of the invention is to provide a unique mounting for the structure above mentioned.

With these ends in view, this invention consists in the details of construction and 40 combination of elements hereinafter set forth and then specifically designated by the claims.

In order that those skilled in the art to which this appertains, may understand how 45 to make and use the same, I will describe its construction in detail, referring by numerals to the accompanying drawing forming a part of this application, in which:

Fig. 1, is a rear face view of the outer 50 end of a musical instrument neck and head piece showing my invention applied thereto with one of the keys and the outer plate removed to illustrate details of construction of the invention.

Fig. 2, is a side elevation or edge view 55 thereof with a portion broken away and shown in section to illustrate the location and arrangement of one of the devices in the head piece.

Fig. 3, is an enlarged fragmentary section 60 view of one of the tuning pegs removed from the instrument.

In carrying out my invention as here embodied, 2 represents the neck of a stringed musical instrument of the banjo type from 65 which projects the head piece 3 and in the back of this head piece are formed a number of recesses 4 each communicating with a hole 5 through the front of the head piece.

These recesses are to receive the tuning 70 peg structure which includes two parallel spaced plates 6 and 7, the former being termed the inner plate and the latter the outer plate. The outer plate is of greater 75 length than the inner plate, or in other words, has a lug 8 at each end projecting over the woodwork of the head piece beyond the ends of the recesses in order that said plates may be secured to the head piece by means of suitable attaching devices 9 such 80 as screws or their equivalent. The two plates are held together but in spaced relation by means of suitable fastening devices 10.

Between the plates is mounted a tuning 85 peg gear 11 carrying the tuning peg 12 which is preferably formed as an integral part of the gear and projects through a hole 13 in the inner plate and one of the holes 5 in the front face of the head piece. Projecting from the face of the gear 11 opposite that from which the tuning peg extends but in endwise alignment with said tuning peg is a trunnion 14 preferably formed integral with the gear 11 and this trunnion 95 is adapted to seat in a recess 15 in the center of the key pinion 16 which is also mounted between the plates 6 and 7. This pinion preferably has a flange 17 which bears against the inner face of the outer plate 7 and 100 is further provided with a polygonal hub 18 projecting through a hole 19 in the outer plate 7. The hub 18 is adapted to register with a similarly shaped recess 20 in the key base 21 but said recess is of greater depth 105 than the length of the hub to permit the parts to be drawn toward each other in order that the key base and pinion flange may be

forced into close contact on opposite faces of the plate 7 for adding friction between these parts.

A key or finger piece 22 coacts with the 5 key base 21 and has a screw 23 passing through the finger piece of the key and the key base and threaded into the hub 18 for fastening the parts together.

An intermediate gear 24 and pinion 25 10 are arranged for rotation in unison and are preferably formed integral with oppositely projecting integral trunnions 26 and 27 for mounting in the outer and inner plates 7 and 6 respectively. The intermediate gear 15 24 meshes with the key pinion 16 while the intermediate pinion 25 meshes with the tuning peg gear 11 so that as the key 22 is rotated motion will be transmitted to the tuning peg through the pinion 16, gear 24, 20 pinion 25 and gear 11. By providing the key pinion 16 with the flange 17 and permitting the intermediate gear 24 to engage said flange while the intermediate pinion 25 rests against the inner plate it permits 25 the parts to be adjusted without binding upon the intermediate gear or pinion and eliminating the necessity of great accuracy in the parts.

In assembling this device the tuning peg 30 12 is inserted in the hole 13 in the plate 6 and then the trunnion 27 of the intermediate gear pinion inserted in a hole in the same plate after which the key pinion 16 and the key are fastened to the outer plate 7 and 35 when this is done the outer plate 7 may be placed over the parts on the inner plate 6 until the recess 15 registers with the trunnion 14 and the trunnion 26 registers with a hole in said outer plate. When the parts 40 are in these positions the two plates may be fastened together by attaching or fastening devices 10. The complete structure being assembled it may then be placed in one of the recesses 4 with the projecting ends or 45 lugs 8 of the outer plate overlying the solid part of the head piece beyond the recess and by anchoring suitable fastening devices such as screws 9 in the head piece the tuning peg structure will be held in 50 place.

It will be particularly noted that such a structure provides for the tuning peg proper 12 and the key or finger piece 22 being in direct endwise alignment so that to the 55 casual observer the appearance is identical with that of the ordinary tuning peg and with the skilled musician both the key and tuning peg are in the same places as he is accustomed to use them. The reduction in 60 speed of rotation between the tuning peg 12 and its key permits the strings to be very accurately tuned and as the reduction here shown is in the ratio of four to one even

though the key is turned one complete revolution the tuning peg will be rotated but a 65 quarter of a turn. In the ordinary tuning peg it sometimes happens that due to adhesion an extra amount of power is required to start the key and before the movement can be stopped the string will 70 have been either tightened or loosened too much. This disadvantage is entirely overcome by the structure herein described while providing very accurate tuning of the string. 75

Of course I do not wish to be limited to the exact details of construction as herein shown as these may be varied within the limits of the appended claims without departing from the spirit of my invention.

Having thus fully described my invention, what I claim as new and useful is:

1. The combination with a head piece of a stringed musical instrument having a recess in the rear thereof and a hole passing through the front and communicating with the recess, of a pair of parallel plates held in spaced relation, one of said plates being housed in the recess and portions of the other plate projecting over the rear face of the headpiece beyond the recess boundary, means to attach the outer plate to the headpiece, a train of gears between the plates, a tuning peg carried by one of the gears and projecting through the hole in the headpiece, and a key in endwise alignment with the tuning peg and carried by another of said gears whereby motion may be transmitted from the key to the tuning peg at a reduced ratio.

2. A tuning peg structure comprising a 100 pair of plates, a key pinion located between said plates, a polygonal hub carried by said pinion and projecting through one of the plates, a key, means for securing said key to the hub of the key pinion, said key pinion having a recess therein opposite the hub, an integral intermediate gear and pinion located between the plates and so located that the gear meshes with the key pinion, oppositely disposed trunnions on 105 said intermediate gear and pinion for journailling the same in the plates, a tuning peg gear located between the plates concentric with the key pinion and meshing with the intermediate pinion, a trunnion on the peg gear registering with the recess in the key pinion, a tuning peg carried by the peg gear and projecting through the other plate, said tuning peg being in direct alignment 110 with the key and means for securing the plates in spaced relation to hold the parts in their respective positions.

In testimony whereof, I have hereunto affixed my signature.

HARRY W. WEYMANN.
